(57) **CLAIM**

The ornamental design for an electric saw, as shown and described.

DESCRIPTION

FIG. 1 is a perspective view of an electric saw showing my new design;

FIG. 2 is a right side view thereof;

FIG. 3 is a left side view thereof;

FIG. 4 is a front view thereof;

FIG. 5 is a rear view thereof;

FIG. 6 is a top view thereof;

FIG. 7 is a bottom view thereof; and,

FIG. 8 is a partially enlarged view showing the area "8" in FIG. 7.

The dot-dash broken lines indicating an enlargement portion of the design form no part of the claimed design.

The even broken lines depict portions of the electric saw that form no part of the claimed design.

1 Claim, 8 Drawing Sheets
